UNITED STATES PATENT OFFICE.

OLIVER P. GREENWOOD, OF BILLERICA, MASSACHUSETTS, ASSIGNOR TO FARRINGTON MANUFACTURING COMPANY, OF JAMAICA PLAIN, MASSACHUSETTS, A CORPORATION OF MAINE.

COVERED BOX AND LIKE ARTICLE.

Original application filed May 3, 1920, Serial No. 378,554. Divided and this application filed March 19, 1921, Serial No. 458,686.

To all whom it may concern:

Be it known that I, OLIVER P. GREENWOOD, a citizen of the United States, and resident of Billerica, county of Middlesex, State of Massachusetts, have invented an Improvement in Covered Boxes and like Articles, of which the following description, in connection with the accompanying drawing, is a specification, like characters on the drawing representing like parts.

This invention relates to improvements in covered articles, particularly covered sheet metal boxes such as are employed as jewelry boxes and for similar purposes, wherein the box is covered with fibrous materials, such as leather, cloth, velvet, imitation leather, paper, etc., or other covering material.

One of the objects of the invention is to provide a covered article of the class described in which the covering is secured to the body of the device and securely held in place thereon without the use of adhesive.

The invention is particularly advantageous, first, in that it eliminates the necessity for the use of adhesive; second, in that it produces an article in which the covering material is retained in its original condition uninjured or unaffected by an adhesive or by heat; and third, in that it produces an article in which the covering material is perfectly fitted to the surface by a mild tension applied to the covering and retained in position when once applied. The invention results in simplifying the construction of the article and producing one of superior finish.

The object and nature of the invention will more fully appear from the following description and accompanying drawings and will be particularly pointed out in the claims.

A preferred embodiment of the invention is illustrated herein as applied to the casing of a jewelry box.

In the drawings:

Fig. 1 is a vertical sectional view through the body of a box or receptacle resting upon a sheet of covering material which also is illustrated in section;

Fig. 2 is a similar sectional view showing the covering bent to conform to the body and outer walls of the box with the edges of the covering overlying the upper edges of the walls of the box;

Fig. 3 is a similar view illustrating the edges of the covering empaled upon projections extending upwardly from the inner walls of the box;

Fig. 4 is a similar sectional view showing the empaling members bent downwardly to impose and maintain a tension upon the covering material; and,

Fig. 5 is a perspective view of a covered box.

The invention contemplates broadly the production of a covered article, such as a jewelry box, in which the covering material is retained upon the body by empaling members which preferably are integral with the box and so positioned as to engage the covering material and retain it in position upon the box. Preferably the empaling members are formed integral with the article and present points projecting toward the edge thereof, but which are adapted to be bent away from the edge after having been passed through the covering, thereby imposing a tension upon the covering.

The invention in its broadest sense, however, includes the use of empaling members having their ends extending in a direction away from the edge of the article. In such broad construction the covering material may either be first engaged by the empaling members before the latter are bent down as above described, or the empaling members may be positioned with their points extending away from the edge of the article and the material stretched in any suitable manner, and empaled thereupon.

In the embodiment of the invention illustrated in Fig. 1 the receptacle comprises a body 1 having a bottom 2 and side walls 3, the side walls being stamped to form triangular empaling members 4 having their points 5 extending toward the upper edge 6 of the walls of the receptacle. The covering material 7 is placed snugly against the base of the receptacle, or if desired a filling (not shown) may be interposed between the covering material and the base of the receptacle. The edges 8 of the covering project beyond the side walls of the receptacle a sufficient distance to enable the same to be carried up along the outer sides of said walls, across the upper edge thereof as illustrated in Fig. 2, and downwardly along the inner sides of

the walls until they are engaged by the empaling members 4 as illustrated in Fig. 3. The empaling members 4 are then bent downwardly as illustrated in Fig. 4 so that 5 their ends extend in parallelism with, or inclined toward, the inner sides of the walls of the receptacle. When the empaling members are thus bent downwardly, after the edge of the covering material has been 10 engaged by them, they exert a tension upon the material which serves to stretch the same snugly around the outer surface of the base and side walls of the receptacle and since these empaling members, when bent downwardly, remain in such position the tension 15 upon the covering material is maintained. Thus the covering material is perfectly fitted upon the outer surface of the article and securely held in place.

20 By reason of this construction it is unnecessary to use adhesive such as has heretofore been employed in the production of covered articles of this character and, consequently, the necessity for the use of heat 25 to render the adhesive temporarily tacky is eliminated. As a consequence, the likelihood of injury to the covering or the penetration into the covering of the adhesive, which some times has heretofore occurred, 30 is entirely obviated.

In the construction of a receptacle of this character any suitable material may be employed. Preferably the body portion of the article is formed of suitable sheet metal 35 of sufficient rigidity to produce a strong receptacle. The covering may be of any suitable material, but preferably is of velvet or other types of cloth commonly used in the covering of jewelry boxes, or leather, but it 40 will be understood that the invention contemplates broadly the use of any suitable covering material.

While it is desirable that the covering shall be applied in the manner above described it will be understood that the empaling members may be first bent downward to the position illustrated in Fig. 4, or if desired may be formed with the points projecting downwardly or away from the edge 50 of the body and the covering material stretched over said empaling members. This may be accomplished where elastic material is employed, or material which may be rendered elastic by soaking with water or other liquid. For example, a leather covering 55 may be secured to the article by sufficiently moistening the leather to cause it to stretch, applying the same to the outer side of the article and stretching the edges over sufficiently to engage the reversely positioned 60 projecting empaling members, the leather when dried being caused to shrink sufficiently to stretch the same snugly against the outer sides of the article.

65 While articles embodying my invention

may be produced by hand operations, the same preferably is produced by a machine such as that disclosed in my prior application Serial Number 378,554 of which the present application is a division. As disclosed in that application the article is placed upon the cover and then forced into a suitable die, formers being provided to fold inwardly the edges of the cover, and a plunger employed to force the cover upon 70 the empaling members and finally bend the empaling members downwardly as illustrated herein.

It will be understood that the embodiment of the invention disclosed herein is of an 80 illustrative character and that various modifications in form, construction and arrangement of the essential parts may be made within the spirit and scope of the following claims.

Having thus described my invention, what I claim as new, and desire to secure by Letters Patent, is:

1. A covered article of the class described comprising a body of rigid material having 90 a covering of flexible material secured to it by pointed empaling members integral with said body which penetrate said covering material.

2. A covered article of the class described 95 comprising a body, a sheet of covering material stretched snugly against the surface thereof and retained in stretched position by pointed empaling members projecting from said body through said covering.

3. A covered article of the class described comprising a sheet metal body having integral pointed empaling members extending away from the edge of said body and a sheet of covering material bent around the 105 edge of said body and engaged by and retained in position by said empaling members.

4. A covered article of the class described comprising a sheet metal body, a covering 110 stretched snugly against one side thereof and empaling members integral with said body engaging said covering and reversely bent to maintain a tension upon said covering.

5. A covered member for receptacles comprising a sheet metal body, a covering stretched snugly against one side thereof, empaling members integral with said body extending from the opposite side thereof 120 engaging said covering and having their ends bent away from the edge of said body whereby tension is imposed and permanently maintained upon said covering.

6. A covered member for receptacles comprising a sheet metal body having a base and side walls, empaling members projecting from the inside of said side walls in a direction away from the edges thereof and a sheet of covering material having its edges 125 130

extending around the edges of said side walls and engaged by said retaining members.

7. A covered member for receptacles comprising a sheet metal body having a base and side walls, provided with inwardly extending empaling members stamped therefrom with the points extending toward the edges of said side walls, a sheet of covering material stretched snugly against the outside of said body and retained in stretched condition by said empaling members when reversely bent to cause their ends to extend away from the edges of said side walls.

8. A fabric covered metal box in which the sheet of covering material extends at its edges over the edges of the box walls and lies against the inside of the walls and is held stretched snugly against the outer surface of the box by a plurality of pointed tabs struck out of the metal of the box walls, passed through the covering material and bent down over the material against the inside of and away from the edges of the box walls.

In testimony whereof, I have signed my name to this specification.

OLIVER P. GREENWOOD.
